UNITED STATES PATENT OFFICE.

OSCAR WINTER, OF PHILADELPHIA, PENNSYLVANIA.

TABLE-TOP PROTECTOR.

1,399,371.

Specification of Letters Patent

Patented Dec. 6, 1921.

Application filed May 3, 1917. Serial No. 166,208.

To all whom it may concern:

Be it known that I, OSCAR WINTER, a citizen of the United States, residing at Philadelphia, in the county of Philadelphia and State of Pennsylvania, have invented 5 certain new and useful Improvements in Table-Top Protectors; and I do hereby declare the following to be a full, clear, and exact description of the invention, such as 10 will enable others skilled in the art to which it appertains to make and use the same.

The object of the invention is the improvement of the well known table top protector or mat comprised of slightly separated folding sections, each section having two layers of asbestos cemented to an intermediate integral sheet, the said sections being inclosed in two outer sheets of flexible material and a row of stitches passed 20 through the said integral sheet and the two outer sheets between the slightly separated sections, thus forming folding lines or hinges.

It has been found that in the use of such 25 protectors or mats the asbestos layers soon break on irregular lines resulting in the formation of uneven surfaces, that wrinkles and projecting folds in the outer sheets soon develop each side the folding lines, and that 30 the sections become stretched apart and wabbling with relatively wide and deep creases on the folding lines, the edges bounding said creases presenting obstructions to dishes and goblets moved along the surface 35 of the mat and overturning or spilling the contents thereof.

I have obviated the above mentioned imperfections by constructing a protector or mat of sections of specially prepared soft 40 non-heat-conducting wool felt with an intermediate water and moisture-proof strip of material between the same on the folding line, adding to the outer surfaces of the 45 wool felt layers of water and moisture-proof fabric and firmly stitching said five layers together each side of the folding line with two separated rows of stitches. Finally, I have inclosed the said body portions thus formed within two outer sheets of canton 50 flannel or other flexible cloth, ornamental or otherwise, stitched the said intermediate strip and outer coverings together between the sections on the folding line, then (which is of importance) applied two rows of 55 stitches to all the layers of material, outer and inner, one row each side and a short dis-

tance from the slightly separated edges of the wool felt layers. The presence of these latter rows of stitches limits the stretching of the fabrics forming the hinge to the parts 60 thereof between said rows of stitches, which is sufficient to permit folding of the sections without tearing or rending the fabric. As a result of this construction folds and wrinkles in the outer covering are prevented, the 65 edges of the inner sections do not project, the wabbling of the sections is prevented, and there are no wide and deep creases between the sections when the protector is unfolded and in use.

To the outer edge of the mat or protector a binding is applied in the well known way. The shapes of these units are immaterial, but two half circular parts placed edge to edge may serve to cover a round top table, 75 and units of suitable shape may be used in addition when the top of an extension table is to be protected from heat and moisture.

In conformity with the above exposition of the object of my improvement, the invention 80 consists in certain novelties of construction and combinations of parts as herein set forth and claimed.

The accompanying drawing illustrates the embodiment of the improvement, the parts 85 being constructed and combined according to the best mode of procedure I have so far devised for the purpose.

Figure 1 is a plan view of a part of an entire protector or mat, showing three folding lines or hinges.

Fig. 2 is an edge view of the protector of Fig. 1 as it appears when folded.

Fig. 3 is an enlarged section of Fig. 1, disclosing one of the hinges, with parts 95 broken away to illustrate the relative positions of the several layers or sheets of material.

Fig. 4 is an enlarged section on line $x-x$ of Fig. 1.

The elements which constitute the protector or mat are designated as follows:

A A are two layers or sheets of wool felt with an intermediate strip of water and moisture-proof fabric B extending the entire length of each hinge or folding line. C C are layers or sheets of oilcloth or other waterproof fabric corresponding in size or area with the layers or sheets A A and they are located upon the outer surfaces of said sheets. These parts A, B and C are secured together by the two lines of stitches 1, 1, as

shown by Figs. 3 and 4. Outside the parts as so united are outer layers or sheets of canton flannel D D or other suitable flexible fabric, ornamental or otherwise. Two rows 5 of stitches 2, 2 are passed through the outer coverings D D and strip B, the stitches drawing the material of coverings D D down slightly between the edges of the wool 10 felt A A. Each side of the folding line or hinge a row of stitches 3 is passed through all the layers of material. Finally, a binding 15 E is applied to the outer edge of the assembled layers or sheets.

A protector or mat as thus constructed 20 cures the imperfections appertaining to the protector or mat hereinbefore described.

The wool felt prevents the transmission 25 of heat to the table. The oilcloth and strip B prevent the transmission of water or moisture. The two rows of stitches 3, 3 prevent the formation of folds or wrinkles in 30 the exterior covering outside the hinges, confine the stretching of the material to the fabrics between said two rows of stitches when the protector or mat is folded, and hold the sections in place so there are no wide creases or loose wabbling of the parts each relative to the other. The entire protector or mat is soft and flexible, maintains 35 its shape and level surface without the use of glue or cement, and as a whole constitutes a very superior article for the purpose designed.

What I claim is:

- 35 1. The combination in a table top protector having two outer sheets of flexible material, of a plurality of sections of non-heat-conducting sheets slightly separated from one another at their adjacent edges 40 and arranged between said outer sheets, a row of stitches passed through the two outer sheets on the folding line between the adjacent edges of the non-heat-conducting material; and rows of stitches, 3, 3, passed 45 through all the sheets of material one row on each side and adjacent to a folding line or hinge, for the purpose set forth.
2. The combination in a table top protector having two outer sheets of flexible 50 material, of an inner strip of flexible material B, a plurality of sections of non-heat-conducting sheets placed on each side of and overlapping said strip B and slightly separated from each other, stitches uniting the 55 non-heat-conducting material and the strip B, a row of stitches uniting the two outer sheets of flexible material between the edges

of the non-heat-conducting material, said stitches also passing through the strip B, and two rows of stitches 3, 3 through all the 60 sheets one row each side of the folding line.

3. The combination in a table top protector, of a plurality of sections of non-heat-conducting sheets of material slightly separated from one another, two outer sheets 65 of flexible material secured to said sections at their edges, a row of stitches uniting said outer sheets between the edges of the non-heat-conducting material, two sheets of oilcloth C C; rows of stitches 1, 1 passed 70 through both sheets of oilcloth and the non-heat-conducting material; and two rows of stitches 3, 3 passed through all the sheets one row each side of a folding line and adjacent to the slightly separated edges of 75 the sections of the non-heat-conducting sheets of material.

4. The combination in a table top protector, of two outer sheets of flexible material, a plurality of sections of non-heat-conducting material arranged between said outer sheets with their edges slightly separated, sheets of material impervious to moisture located between the non-heat-conducting material and an outer sheet of 80 flexible material, a row of stitches uniting said outer sheets between the edges of the non-heat-conducting material, and two rows of stitches through all the sheets of material 85 one row being located each side of a folding 90 line.

5. The combination in a sectional protector or mat, of a plurality of sections of non-heat-conducting sheets arranged edge to edge, strips of material interposed between the edges of said sheets of non-heat-conducting material, outer sheets of oilcloth each of substantially the same area as the sections of non-heat-conducting material, two sheets of outer flexible material 95 100 constituting a covering, stitches uniting the said sections of non-heat-conducting material the oilcloth sheets and the outer coverings at their outer edges, and rows of 105 stitches passed through the outer coverings and the said interposed strips of material at the abutting edges of the sections of non-heat-conducting sheets.

In testimony whereof I affix my signature.

OSCAR WINTER.
